TWO-STROKE ENGINE

Auguste Louis René Bernard, deceased, late of
Rueil-Malmaison, France, by Renée Bernard,
née Bournonville, executrix, Paris, France

Application January 25, 1935, Serial No. 3,528
In Belgium February 9, 1934

10 Claims. (Cl. 123—71)

The present invention relates to two stroke engines of the type in which at least a portion of the gases (for instance air) to be fed to the engine passes through the inside of the base of the cylinder before entering the combustion chamber of said cylinder. The invention is more particularly, although not exclusively concerned with engines of this type which include, for each cylinder, an air feed pump the piston of which is not rigid with the cylinder piston, as described in the French Patent No. 688,522 of August, Louis René Bernard, filed September 7, 1933.

The object of the present invention is to provide an engine of the type above referred to in which the gases admitted to the engine cylinder do not contain too high a percentage of oil vapors driven along by said gases as they pass through the engine crank-case.

The essential feature of the present invention consists in providing the engines of the type above mentioned with a partition, provided with a hole for the passage of the connecting rod, adapted to separate from the inside of the crankcase the gases to be fed to the engine cylinder through the inside of the base of said cylinder.

Other features of the present invention will result from the following detailed description of a specific embodiment thereof.

A preferred embodiment of the present invention will be hereinafter described, with reference to the accompanying drawings, given merely by way of example, and in which:

Fig. 1 is a vertical sectional view at right angles to the axis of the crank-shaft of the upper part of a vertical internal combustion engine of the two-stroke type made according to the present invention;

Fig. 2 is a sectional view on the line II—II of Fig. 1;

Fig. 3 is a sectional view on the line III—III of Fig. 2.

The two stroke vertical engine shown by way of example is so devised that the air to be fed to the engine is compelled to pass through the inside of the base of the engine cylinder 1, that is to say under the end face of the driving piston 2 before entering the combustion chamber of said cylinder.

For this purpose use is made of some of the arrangements disclosed by the French patent above referred to in order to obtain an engine in which the whole of the air to be fed to the cylinder is caused to flow through the lower opening of cylinder 1.

An engine of this type includes an air feed

pump the piston 3 of which is disposed around the base or lower part of the driving cylinder 1. This piston 3 is driven through a cinematic gear including a bell crank lever 4 one arm of which is connected, for instance through a connecting rod 5, with said piston 3, and the other arm of which is connected, through a rod 6, to an axis 7 carried at a suitable point by the connecting rod 8 interposed between piston 2 and the crank-shaft. This gear thus causes the piston 3 of the air pump to be actuated out of phase with the driving piston 2.

The intake of the air pump is controlled by the driving piston itself, the skirt of which has a lower edge 9 and is provided with ports 10. The inflow of air to the pump takes place through ports 11 provided in the lower part of cylinder 1 and through the inlet ports of said cylinder, the air admitted into said pump coming from the space below the piston end.

According to the prior art, in an engine of this kind, the external air was allowed to enter freely into the crank-case (eventually after having been freed from dust) and to flow therethrough, this air driving along with it a considerable amount of vapors, and even of droplets, of the lubricant present in said crankcase. This resulted, in some cases, in the engine getting rapidly dirty, and especially in the packing rings of the driving piston gumming up after a short time.

On the contrary, according to the present invention, there is provided, under the base of the cylinder 1, a partition, provided with a hole for the passage of the engine connecting rod, and adapted to separate from the inside of the crankcase, the air to be fed to the engine cylinder through the lower aperture of said cylinder.

For this purpose, there is provided around the lower part of cylinder 1 a partition 12 limiting a space 13 which surrounds said cylinder except at the place where passes the above mentioned connecting rod 5 through which the piston 3 of the air feed pump is actuated.

On the lateral face of this partition there is provided at least one passage 15 adapted to connect said space 13 with a conduit 16 which constitutes the air intake tube. Preferably, an air purifier is provided in said conduit.

A partition 17, provided with a passage 18 for the connecting rod 8 of the engine is fixed to the lower edge of partition 12.

Of course, the whole shall be so devised as to reduce as much as possible the passages connecting the inside of the casing with the lower part of the engine cylinder.

For instance, if it is necessary to interrupt partition 12, as shown in the drawings, for affording a passage for the gear that controls piston 3, this partition will be so shaped that its edges extend as near as possible either to the base of the engine cylinder, or to a prolonged part 19 with which said piston 3 is advantageously provided.

However, it should be noted that it is not at all necessary to ensure full fluidtightness between the inside of the crank-case and the base of the engine cylinder, the only condition to be obtained being that the whole of the air fed to the engine cylinder does not pass through the crank-case where it would drive along with it too large an amount of lubricant.

There is no serious disadvantage in letting a certain portion of the air sucked in to the engine cylinder come from the engine crank-case. This portion of the air fed to the engine will always remain very small if the crank-case itself is closed in a fluidtight manner, that is to say if no continuous air stream is allowed to flow therethrough.

Aperture 18 is necessarily made of comparatively large size, but this does not involve any disadvantage. This aperture should be so devised as to prevent lubricant projected from the crank-case from passing therethrough. For this purpose partition 17 is, for instance, provided with an inwardly extending edge 20 of a relatively great height, for instance one half of the bore of the cylinder.

This bent edge 20 will further serve to deflect toward the end of the driving piston the air having passed under the lower edge of the engine cylinder. This air will therefore be driven away from aperture 18. On the other hand, it will ensure the cooling of the driving piston.

It is believed that, in view of the preceding description and explanations it is unnecessary to further describe the operation of the engine according to the present invention.

In the specific embodiment above described, partition 12 is fixed in a fluidtight manner to the frame 14 of the engine, but this partition might be fixed either to the base of the engine cylinder or to the base of the driving piston if the air to be fed to the engine were to penetrate into the base of the engine cylinder through ports suitably provided for this purpose instead of flowing under the lower edge of said lower part of the cylinder.

While the above description discloses what is deemed to be a practical and efficient embodiment of the present invention, it should be well understood that it is not to be limited thereto as there might be changes made in the arrangement, disposition and form of the parts without departing from the principle of the present invention as comprehended within the scope of the accompanying claims.

What is claimed is:

1. A two-stroke internal combustion engine which comprises, in combination, at least one cylinder, a piston in said cylinder, a crankshaft, a connecting rod between said crankshaft and said piston, a crankcase, a pump having an annular cylinder and an annular piston surrounding said first mentioned cylinder, for feeding air to the combustion chamber of the first mentioned cylinder, transmission means operative by said crankshaft for actuating said second mentioned piston, means including the lower part of said first mentioned cylinder for feeding air from the outside of said crankcase to said pump, a parti-

tion for separating the lower part of said first mentioned cylinder from said crankcase, said partition including an annular wall surrounding said lower part of the first mentioned cylinder except, on one side thereof where a passage is left for said transmission means, and extending below the lower edge of said first mentioned cylinder, and a disc-shaped part provided with a hole for the connecting rod, the edge of said hole being bent inwardly.

2. A two-stroke internal combustion engine comprising, in combination, at least one cylinder, a piston in said cylinder, a crankshaft, a connecting rod between said crankshaft and said piston, a crankcase, a pump having a piston for feeding air to the combustion chamber of said cylinder, means for actuating said second piston, means for conducting air to said pump from the interior of that part of said cylinder which is located on the side of said first piston opposite the combustion chamber, a partition separating the interior of said cylinder from said crank case, said partition having a hole for said connecting rod, and means comprising openings for the passage of fresh air into the interior of said cylinder.

3. A two-stroke internal combustion engine which comprises, in combination, at least one cylinder, a piston in said cylinder, a crankshaft, a connecting rod between said crankshaft and said piston, a crankcase, a pump outside of said cylinder having a piston for feeding air to the combustion chamber of said cylinder, means for actuating said second piston, said cylinder having openings in its wall, said openings connecting the interior of said cylinder with the interior of said pump, said openings being closed and opened by said first mentioned piston, a partition for separating the interior of said cylinder from said crankcase, said partition having a hole for said connecting rod, and means comprising openings for the passage of fresh air into the interior of said cylinder.

4. A two-stroke internal combustion engine comprising, in combination, at least one cylinder, a piston in said cylinder, a crankshaft, a connecting rod between said crankshaft and said piston, a crankcase, a pump, having a piston, for feeding air to the combustion chamber of said cylinder, transmission means operative by said crankshaft for actuating said second piston out of phase with respect to the movement of the first piston, means for conducting air to said pump from the interior of that part of said cylinder which is located on the side of said first piston opposite the combustion chamber, a partition separating the interior of said cylinder from said crankcase, said partition having a hole for said connecting rod, and means comprising openings adapted to let fresh air into the interior of said cylinder.

5. A two-stroke internal combustion engine comprising, in combination, at least one cylinder, a piston in said cylinder, a crankshaft, a connecting rod between said crankshaft and said piston, a crankcase, a pump for feeding air to the combustion chamber of said first cylinder, said pump comprising an annular cylinder and an annular piston surrounding said first cylinder, transmission means operative by said crankshaft for actuating said second mentioned piston out of phase with respect to the movement of the first piston, said first cylinder having openings in its wall for connecting its interior with the interior of the second cylinder, said openings being closed and opened by said first piston, a partition sep-

5 arating the interior of said first mentioned cylinder from said crankcase, said partition having a hole for said connecting rod, and means comprising openings for the passage of fresh air into the interior of said first cylinder.

6. A two-stroke internal combustion engine comprising, in combination, at least one cylinder, a piston in said cylinder, a crankshaft, a connecting rod between said crankshaft and said piston, 10 a crankcase, a pump for feeding air to the combustion chamber of the first cylinder, said pump comprising an annular cylinder and an annular piston surrounding said first cylinder, transmission means operative by said crankshaft for actuating said second piston out of phase with respect to the movement of the first piston, said first cylinder having openings in its wall for connecting its interior with the interior of the second cylinder, said openings being closed and 15 opened by said first piston, a partition separating the lower part of said first cylinder from said crankcase, said partition including an annular wall surrounding said lower part and a disc-shaped bottom portion, said bottom portion having 20 a hole for the connecting rod, said annular wall having an aperture on one side thereof for the passage of said transmission means, said annular wall and said bottom portion extending below the lower edge of said first cylinder so as to 25 form an air passage, said annular wall having at least one opening for permitting fresh air to pass through said air passage into the interior of said first cylinder.

7. A two-stroke internal combustion engine comprising, in combination, at least one cylinder, a piston in said cylinder, a crankshaft, a connecting rod between said crankshaft and said piston, a crankcase, a pump for feeding air to the combustion chamber of the first cylinder, said 30 pump comprising an annular cylinder and an annular piston surrounding said first cylinder, transmission means operative by said crankshaft for actuating said second piston, said first cylinder having openings in its wall for connecting its interior with the interior of the second cylinder, said openings being closed and opened by 35 said first piston, means comprising openings for the passage of fresh air into the interior of said

first cylinder, and a partition surrounding the lower part of said first cylinder so as to separate the inside of the lower part of said first cylinder from said crankcase, said partition having an aperture on one side thereof for the passage of 5 said transmission means and a hole for said connecting rod.

8. An internal combustion engine according to claim 7 in which the edge of the hole for the connecting rod is bent inwardly toward the cylinder 10 of the engine.

9. A two-stroke internal combustion engine comprising, in combination, at least one cylinder, a piston in said cylinder, a crankshaft, a connecting rod between said crankshaft and said 15 piston, a crankcase, a pump having a piston for feeding air to the combustion chamber of said cylinder, means for actuating said second piston, means for conducting air from the interior of that part of said cylinder which is located 20 on the side of said first piston opposite the combustion chamber, a partition separating the interior of said cylinder from said crankcase, said partition having a hole for said connecting rod, the edge of said hole being bent inwardly to- 25 ward the cylinder, and means comprising openings for the passage of fresh air into the interior of said cylinder.

10. A two-stroke internal combustion engine comprising, in combination, at least one cylinder, 30 a piston in said cylinder, a crankshaft, a connecting rod between said crankshaft and said piston, a crankcase, a pump having a piston for feeding air to the combustion chamber of said cylinder, means for actuating said second piston 35 out of phase with respect to the movement of the first piston, means for conveying air to said pump from the interior of that part of said cylinder which is located on the side of said first piston opposite the combustion chamber, a partition sep- 40 arating the interior of said cylinder from said crankcase and having a hole for said connecting rod, and means comprising openings for the passage of fresh air into the interior of said cylinder.
